GARMENT HANGER SUPPORTING MECHANISM FOR WARDROBE TRUNKS

Filed Jan. 18, 1924

UNITED STATES PATENT OFFICE.

WADE H. HARRISON, OF PETERSBURG, VIRGINIA.

GARMENT-HANGER-SUPPORTING MECHANISM FOR WARDROBE TRUNKS.

Application filed January 18, 1924. Serial No. 687,052.

To all whom it may concern:

Be it known that I, WADE H. HARRISON, a citizen of the United States, residing at Petersburg, in the county of Dinwiddie and State of Virginia, have invented certain new and useful Improvements in Garment-Hanger-Supporting Mechanism for Wardrobe Trunks, of which the following is a specification.

10 This invention relates to an improvement in garment hanger supporting mechanism for wardrobe trunks of either the hinged or rigid end type, and has for its primary object to substantially improve and simplify 15 over devices of this general nature.

An additional object of the present invention resides in the provision of a supporting mechanism for garment hangers wherein the same may be slid to a position outwardly of 20 the trunk for thereby allowing ready access to be had to the garments, it being of course obvious that the garments on the hangers may be moved outwardly of the trunk when said support is extended.

25 An additional object of the invention resides in the provision of such a supporting means whereby an outward extension of the same will be prevented when the trunk is closed, means being provided, however, for 30 allowing of an extension of said supporting means when the trunk is opened.

Yet another object of the invention is to provide a garment hanger supporting mechanism for wardrobe trunks wherein the 35 same may be entirely removed from the trunk and associated with a certain co-operative member within a house or other building closet or hung upon a clothes line, for thereby allowing the entire wardrobe to 40 be removed from the trunk and placed in said closet when the traveler reaches his destination, or placed upon said line for airing purposes.

With the above and other objects in view 45 as the nature of the invention will be better understood, the same comprises the novel form, combination and arrangement of parts hereinafter more fully described, shown in the accompanying drawing and 50 claimed.

In the drawing wherein like reference characters indicate corresponding parts throughout the different views,

55 Figure 1 is a fragmentary transverse sectional view taken through the upper end of a wardrobe trunk equipped with my novel

garment hanger supporting mechanism, said garment hanger supporting mechanism being shown in top plan,

60 Figure 2 is a fragmentary vertical transverse sectional view through the trunk for disclosing in front elevation, said garment hanger supporting mechanism,

65 Figure 3 is a top plan view of a specific form of bracket element employed in combination with the present invention, said bracket element adapted to be secured within a closet for allowing the garment hanger supporting mechanism to be positioned therein, and this while the garment hangers 70 are associated therewith,

75 Figure 4 is a side elevational view of said bracket, the same being shown as actually in use, and

Figure 5 is a detail section taken substantially on the line 5—5 of Figure 1.

Now having particular reference to the drawing, the particular type of wardrobe trunk with which my present garment hanger supporting mechanism is to be associated, embodies a casing 5 the front wall 6

80 of which is hingedly secured thereto for allowing ready access to be had to the interior of the trunk when the same is opened. The upper end of said casing is as is well known, 85 opened, and provided with a hinged lid 7.

The present invention per se, embodies the provision of a sheet metal strap 8 that is to be riveted or otherwise suitably secured to the inner side of the rear wall of the casing 90 5, and this directly at the upper open end thereof. Secured to said strap 8 intermediate its ends is a plate 9 that carries at its upper end and adjacent one edge a forwardly extending solid bar 10 over which is freely 95 slidably movable, a tubular bar 11.

Formed laterally with respect to said tubular bar 11 and extending parallel therewith is a sheet metal strip 12 that is formed at its opposite ends with inwardly extending 100 portions 13 and 14 whereby said metal strip may be rigidly secured to the tubular bar 11.

Arranged between the metal strip 12 and tubular bar 11 and extending parallel therewith is a pair of spaced metal strips 14' and 16, respectively, which terminate short of the front end of said metal strip 12, these first mentioned metal strips 14' and 16, being integrally joined together at their inner ends by a connecting portion rearwardly 110 of the inwardly bent portion 13 of the metal

strip 12 and that is rigidly secured to the before mentioned plate 9 secured to the metallic strip 8.

The tubular bar 11 is formed upon its inner side and adjacent its front end with a small opening 15 that registers with a notch in the solid bar 10 when the same is moved rearwardly to its limit of movement upon said bar, or in other words, to the position shown in Figure 1, for thereby allowing the spring pressed plunger 17 of a conventional form of latch mechanism 18 to engage through the opening in the tubular bar and consequently projecting into the notch of the solid bar 10 for obviously preventing a sliding movement of the tubular bar with respect to the solid bar, and this especially when the trunk is in its closed position.

The latch mechanism 18 previously described is suitably secured to the inner side of the inwardly bent portion 14 of the metal strip 12, and the latch bolt 17 thereof carries an outwardly projecting lug 19 that extends through a slot in said inwardly bent portion 14 of the metal strip 12 for obviously allowing the bolt to be retracted and the tubular bar 11 consequently slid forwardly upon the solid bar 10 and this when the trunk is open.

The front end of the lowermost metal strip 15 between the before mentioned tube 11 and parallel strip 12 is bent upwardly toward the top strip 14' as indicated by the reference character 20, for obviously engaging the inwardly bent portion 13 of said metal strip 12 for thereby preventing the accidental total displacement of the tubular bar with respect to the solid bar. The top metal strip 14' is of a length slightly less than the length of the lower strip 15 and carries upon its top side a latch mechanism 21 that includes a spring pressed latch bolt 22 for closing the space between the end of the strip 14' and the upwardly bent portion 20 of the strip 15 for manifestly preventing a turning movement of the tubular bar upon the solid bar when the same has been totally extended for consequently preventing the entire disengagement of the tubular bar with respect to the solid bar. However, said latch bolt 22 is equipped with a finger piece 23 for allowing the same to be moved rearwardly whereby the tubular bar 11 may be rotated upon the solid bar 10 through the medium of a hook 24 carried intermediate the ends of the metal strip 12 after which said tubular bar may be entirely removed from the solid bar for allowing the clothes that are carried by the garment hangers 25 which are supported upon the tubular bar 11 to be entirely removed from the trunk and positioned within a closet.

Within the closet is a bracket 26 that includes a forwardly extending horizontal

portion 27 that is provided at its front end with an opening 28 for allowing the before mentioned hook 24 to be engaged therethrough whereby the garment hanger supporting structure may be supported within the closet when the traveler has reached his destination.

The garment hanger to be used in conjunction with the present invention is of a specific construction, the same including the usual wire coat hanger 29, the lower horizontal bar portion of which carries fasteners of the clasp type designated 30-30. Secured to the lower clasps of these elements are the opposite ends of a horizontal bar 31 slidable upon which are trousers clasps 32.

The reason for this particular construction of a garment hanger is to allow the trousers, dresses or other articles of wearing apparel that cannot be placed upon the coat hanger 29 to be folded over the cross bar 31 when the same are placed within a trunk. However, when the mechanism is removed from the trunk said trousers, dresses or other articles of wearing apparel may be removed from the cross bar 31 and hung in an unfolded position through the medium of the clasps 32-32.

It will thus be seen that I have provided a highly novel and efficient form of garment hanger supporting mechanism for wardrobe trunks, as well as an improved form of garment hanger to be employed in conjunction therewith.

I do not wish to be limited to the specific structure shown and described, as in the future practice of the invention, minor changes may be made therein without departing from the spirit and scope of the appended claims.

Having thus described my invention, what I claim as new and desire to secure by Letters Patent is:—

1. In a garment hanger structure, a support, a bar projecting from said support, a second bar telescoped over the first bar, a frame attached to the second bar, a third and fourth bar extending from the support, one on each side of the frame for preventing rotation of the second bar in relation to the first bar, the third bar being longer than the fourth bar and provided with an extension disposed toward the fourth bar.

2. In a garment hanger structure, a support, a bar projecting from said support, a second bar telescoped over the first bar, a frame attached to the second bar, a third and fourth bar extending from the support, one on each side of the frame for preventing rotation of the second bar in relation to the first bar, the third bar being longer than the fourth bar and provided with an extension disposed toward the fourth bar, the fourth bar having incorporated in its end

a latch mechanism including a bolt, spring pressed to normally engage the extension on the third bar.

3. A garment hanger structure including 5 a support, a bar extending from the support, a second bar telescoped over the first bar, both of said bars provided with registerable openings, a third and fourth bar extending from the support in parallel relation to the first two mentioned bars, the third bar being longer than the fourth bar and provided with an extension disposed 10 toward the fourth bar, a latch mechanism incorporated in the end of the fourth bar

and provided with a spring pressed bolt 15 normally engaged with the extension, a frame extending from the second bar and having a portion disposed between the third and fourth bars so as to prevent turning of the second bar on the first bar, and a latch 20 mechanism incorporated in the frame and provided with a spring pressed bolt adapted to engage the openings in the first two mentioned bars so as to hold the second bar in a contracted position over the first bar. 25

In testimony whereof I affix my signature.

WADE H. HARRISON.
